UNITED STATES PATENT OFFICE

GEORGE WILLIAM MEIGHAN, OF NORTH BERGEN, NEW JERSEY

PIPE AND CONDUIT BENDER

Application filed February 20, 1931. Serial No. 517,358.

This invention relates to a machine for manually bending pipes or conduits, whereby to form accurate and uniform bends of predetermined angularity, and also to form offsets and double bends and elbows in said pipes and conduits with ease and dispatch.

It is an object of this invention to provide a simple and efficient machine of this type, which is extensible to accommodate different lengths of pipes or conduits, and which is cheaply and easily manufactured, and otherwise admirably suited for the purpose for which it is designed.

These and other objects of the invention, its nature, and its composition and arrangement and combination of parts will be readily understood by anyone acquainted with the art to which this invention relates upon consulting the following descriptions of the drawings, in which:

Figure 1 is a general side elevation of my improved bending machine showing it positioned to make a right angular elbow in a pipe or conduit.

Figure 2 is a view similar to Figure 1 showing the machine positioned to form an offset in a pipe or conduit.

Figure 3 is a top plan view of the machine of Figures 1 and 2.

Figure 4 is a detail longitudinal vertical cross sectional view taken through the upper groove in Figure 3.

Figure 5 is a similar view taken through the lower groove of Figure 3.

Figure 6 is a perspective view of the track and pipe or conduit support constituting the base of the machine, Figure 6 showing perspective the inner member thereof.

Figure 7 is an end view taken from the left of Figure 3 showing the mounting of the base member shown in Figure 6 within the main base member showing associated with the base member the sliding abutment.

Figure 8 is a transverse vertical cross sectional view taken from the left of the bending blocks transversely of Figure 3.

Figure 9 is a similar view looking toward the left through the bending mechanism.

Figure 10 is a top plan view of the lower bending block.

Figure 11 is a perspective view of the lower, swinging bending block.

Referring in detail to the drawings, the numeral 5 designates generally an open bottomed channel member constituting the main base member of the machine, in which is slidably disposed and adapted to be extended therefrom an inner member 6, which is retained within the main member 5 by means of upturned channel flanges 7 as clearly seen in Figure 7. The member 6 has a longitudinal slot or channel 8 formed in one side thereof to receive a head 9 on a bolt 10 projected through a depending portion 11 on a slide abutment 12 adapted to ride upon the outer face of the base member 5. A set screw 13 projects itself through an opposite side of the member 5 to limit the sliding movement of the inner member 6. Both the member 5 and the member 6 are semi-circularly depressed throughout their length as indicated at 14 to form a guide for the conduit or pipe which is laid therein.

An open frame consisting of side members 15 connect the main base longitudinally spaced from a wide double grooved base section generally designated 16 which consists of a stationary member 17 and an extensible sliding member 18, which member 18 is retained by a set screw 18a projected through one side of the member 17. The upper surfaces of the members 17 and 18 are provided with nested grooves 19 and 20, respectively, the groove 19 being in alignment with and in longitudinal continuation of the groove 14 in the base member 5.

Referring to Figure 10 it will be seen that the inward end of the base member 5 is provided with a lateral extension 21 constituting a bending block and provided with a longitudinal groove 22 aligned with and in longitudinal continuation of the groove 20 in the member 16.

Pivotedly supported at one side of the bending structure is a hand lever 23, the pivotal point being indicated at 24, and on its lower end carries a right angularly disposed arm 25 on the end portion of which is a lateral horizontally extended rectangular block 25a having in its upper face longitudi-

nally and upwardly curved grooves 26 and 27. At the pivotal point 24 there is an oppositely extending right angular arm 28 which carries at its extremity a lateral and horizontally disposed bending block 29 having a downwardly and longitudinally curved groove 30 in its under face. These formations are clearly seen in Figure 11.

An upper bending block 31 having the 10 upwardly curved grooves 32 and 33 is mounted stationary with the base member 5 and spaced thereabove, and to the support thereof of the lever 23 is pivoted in such a way as to bring its curved upper face 34 into coincidental abutment with the lower curved face 35 of the bending block 31, and so as to bring its bending block 29 in a similar relation to the upwardly curved face 36 of the bending block 21, when the handle or hand lever 20 23 is drawn to the left in the drawings.

Straddling the opening of the frame member 15 and attached at one end at 39 and at its other end at 40 to the section 16 of the base structure, is a quadrant 41 whose use 35 will be described.

When it is desired to make an elbow in a piece of pipe or conduit, the desired length of pipe is laid in the groove 14, and the proper measurement of length and position of the bend desired taken by extending the pipe or conduit in coordination with the measuring indicia 42 laid out between the grooves 19 and 20 of the base section 16. The hand lever 23 is then drawn to the left, the 40 sliding abutment 12 having first been positioned as shown in the figures of the drawings to abut the outer end of the pipe or conduit 43, and the movement to the left of the hand lever 23 is continued so as to bring the movable bending block 25 upwardly to draw and press the contacted portion of the pipe or conduit, into the position of angularity desired, the said angularity being predetermined on the quadrant 41, the bending 45 movement being continued until the end of the pipe or conduit has been positioned upon or opposite the predetermined indicia on the quadrant 41. Granting that the same setting of the abutment block 12 obtains, the lengths 50 of pipe or conduit being the same, the bends will be positioned and curved absolutely accurately for all practical purposes by the operation described.

For forming double bends or offsets, the 55 conduit is transferred from its initial position, to the groove 33 of the bending block 31, and this exposes the other end portion of the conduit or pipe to the downward pressing action of the bending block 29, which subjects the conduit or pipe to the groove 22 and the downwardly curved portion thereof 22a whereby the said portion of the pipe or conduit is downwardly bent in exactly the same angle and position as the initially formed 60 bend, thus producing a uniform offset. It

will be obvious that any desired angularity of the offset may be achieved by proper coordination with the scale 42 and the quadrant 41. Obviously the bending block 31 permits uniform results in the bending operation, and it is also obvious that the various grooves, being conformed to the cross section of the pipes to be bent have the tendency to prevent flattening and other undesired deformation of the pipes or conduits during the bending operation.

It is to be definitely understood that I do not desire to limit the application of this invention to the particular modification set out herein to illustrate the principles thereof, and any change or changes may be made in material and structure and arrangement of parts consistent with the spirit and scope of the invention.

What is claimed is:—

1. A tube or bar bending machine of the type described comprising a base of channel form having an open frame at an intermediate point thereof, a stationary bending block adjacent the open frame at one side thereof, and a pivoted lever carrying an upwardly swinging bending block for cooperation with the stationary bending block, and an abutment slidable on the base between the stationary block and the contiguous outer end of the base, and a linear scale on the other end portion of the base, and a quadrant mounted adjacent the bending block having indicia for indicating the angularity of movement of a tube or bar being bent in the machine, and inner slides extensible from the ends of the base.

2. A tube or bar bending machine of the type described comprising a base of channel form having an open frame at an intermediate point thereof, a stationary bending block adjacent the open frame at one side thereof, and a pivoted lever carrying an upwardly swinging bending block for cooperation with the stationary bending block and an abutment slidable on the base between the stationary block and the contiguous outer end of the base, and a linear scale on the other end portion of the base, and a quadrant mounted adjacent the bending block having indicia for indicating the angularity of movement of a tube or bar being bent in the machine, and inner slides extensible from the ends of the base.

3. A tube or bar bending machine of the type described comprising a base of channel form having an open frame at an intermediate point thereof, a stationary bending block adjacent the open frame at one side thereof, and a pivoted lever carrying an upwardly swinging bending block for cooperation with the stationary bending block, and an abutment slidable on the base between the stationary block and the contiguous outer end of the base, said base and said slides having longitudinal tube or bar receiving grooves.

4. A tube or bar bending machine of the type described comprising a base of channel form having an open frame at an intermediate point thereof, a stationary bending block adjacent the open frame at one side thereof, and a pivoted lever carrying an upwardly swinging bending block for cooperation with the stationary bending block, and an abutment slidable on the base between the stationary block and the contiguous outer end of the base, said base and said slides having longitudinal tube or bar receiving grooves.

of the base, and a linear scale on the other end portion of the base, and a quadrant mounted adjacent the bending block having indicia for indicating the angularity of movement of a tube or bar being bent in the machine, said lever having also a downwardly swinging bending block cooperating with a further bending block on the base, for simultaneously upwardly and downwardly bending a tube or bar to the same degree.

In testimony whereof I affix my signature.
GEORGE WILLIAM MEIGHAN.
